[57] **CLAIM**
The ornamental design for a reclining chair, as shown and described.**DESCRIPTION**

FIG. 1 is a perspective view of a reclining chair in the upright position embodying my new design;

FIG. 2 is a front elevation view thereof;

FIG. 3 is a rear elevation view thereof, the broken line showing of the knob and plate is for illustrative purposes only and forms no part of the claimed design;

FIG. 4 is a right side elevation view thereof, the left side elevation being a mirror image thereof;

FIG. 5 is a top plan view thereof;

FIG. 6 is a perspective view thereof with the chair in the partially reclined position; and,

FIG. 7 is a perspective view thereof with the chair in the fully reclined position.
